UNITED STATES PATENT OFFICE.

HENRY C. DURICK, OF WORCESTER, AND JOHN T. BIRD, OF BOSTON, MASSACHUSETTS,
ASSIGNORS TO WORCESTER PAPER BOX COMPANY, A CORPORATION OF MASSA-
CHUSETTS.

FOLDING DISPLAY BOX.

Application filed February 27, 1922. Serial No. 539,376.

To all whom it may concern:

Be it known that we, HENRY C. DURICK and JOHN T. BIRD, citizens of the United States, said Durick residing at Worcester, 5 in the county of Worcester and State of Massachusetts, said Bird residing at Boston, county of Suffolk, and State of Massachusetts, have invented a new and useful Folding Display Box, of which the following 10 is a specification.

This invention relates to a folding box or carton, adapted to form an attractive container for the display of fruit, candy or other articles.

15 It is the general object of our invention to provide a display box which may be easily and cheaply manufactured from material having a finished surface on one side only, and which may be formed substantially or 20 entirely from a single sheet of material.

Another object of our invention is to provide a box of this character which, when folded, will present a finished surface both on the inside and on the outside of the 25 article.

Our invention further relates to the provision of a display card associated with the box together with suitable provision for supporting the card. A further feature consists in providing a support or easel as a 30 part of the box and by use of which the contents may be more advantageously positioned.

Our invention further relates to arrangements and combinations of parts which 35 will be hereinafter described and more particularly pointed out in the appended claims.

Two forms of our invention are shown in the drawings in which—

40 Fig. 1 is a plan view of the unfinished side of the blank from which the box is to be folded;

Fig. 2 is a perspective view showing the box partially folded;

45 Fig. 3 is a perspective view of the folded box;

Fig. 4 is an upper end view of the folded box, looking in the direction of the arrow 4 in Fig. 3;

50 Fig. 5 is a sectional elevation taken along the line 5—5 in Fig. 3;

Fig. 6 is a plan view of the unfinished side of a modification;

Fig. 7 is a perspective view of the modified box partly folded;

Fig. 8 is a perspective view of the completely folded box;

Fig. 9 is an end view thereof, looking in the direction of the arrow 9 in Fig. 8;

Fig. 10 is a sectional elevation taken along 60 the line 10—10 in Fig. 8;

Fig. 11 is a detail sectional plan view taken along the line 11—11 in Fig. 8; and

Fig. 12 is a detail plan view of the easel locking device, looking in the direction of 65 the arrow 12 in Fig. 10.

Referring to the form of our invention shown in Figs. 1 to 5, the blank for this box or carton is preferably formed from a single piece of material which requires only 70 one finished surface. The plan view of this blank shown in Fig. 1 discloses the unfinished side thereof.

This blank comprises an outer bottom portion 20 having a U-shaped slit 21 near the 75 center thereof. Lateral extensions of the bottom 20 form outer sides 22 and 23 and inner sides 24 and 25. The outer sides 22 and 23 are provided with locking flaps 26 and 28.

An extension 29 from the end of the inner side 24 forms the inner upper end of the box and the lateral extension 30 of the part 29 is adapted for use as a display card upon which suitable advertising matter or 85 decorative printing may be placed.

The outer side 23 is provided with an extension comprising an outer upper end 31, an end flap 32, a lower edge flap 33 and a flap 34 adapted for use as a brace for the 90 display card 30.

The portion of the flaps extending from the lower edge of the outer bottom 20 comprises an outer lower end 35, an inner lower end 36, and an inner bottom portion 37. 95 The length of the portion 37 may be such as to constitute the entire inner bottom or a portion only thereof, as may be advisable under specific conditions.

A narrow extension from the upper edge 100 of the outer bottom forms an easel or support 38 and an easel brace 39. The several parts of the blank are separated by scored lines as indicated in the drawing to facilitate the folding of the box.

When the blank above described is folded,

55

65

70

80

85

95

105

it provides a box having the sides and ends of double thickness and displaying a finished surface both on the inside and on the outside of the box. The bottom of the box is also of double thickness throughout a greater or less portion of its length. The display card 30 projects upwardly from the top edge of the box and is sustained in this position by the flap or brace 34 on the outer upper 10 end portion 31.

In folding the box, the sides are first folded perpendicular to the bottom and the inner sides may then be folded within the outer sides. The lower end portion is then 15 folded around the locking flaps 26 and 28 of the sides, holding the sides in their folded position as indicated in Fig. 2 in which figure, however, the inner side 24 is shown raised to indicate its direction of movement.

20 The inner upper end 29 is then folded to the position shown in Fig. 3, after which the outer end 31 is brought into position and its flaps 32 and 33 are inserted to lock the parts together. The easel 38 and its 25 brace 39 are positioned as shown in Fig. 5 to support the box at a convenient angle for displaying its contents.

While we have described a convenient method of folding the box, it will be obvious 30 that the exact order of the steps may be considerably varied without inconvenience.

The form of our improved box shown in Figs. 6 to 12 is in general substantially similar to the form previously described.

35 The blank comprises an outer bottom 40, outer sides 41 and 42, inner sides 43 and 44, locking flaps 45 and 46, an inner upper end 47, an outer upper end 48, outer and inner lower ends 49 and 50 and an inner bottom 40 51, all as in the previous form.

End flaps 52 and 53 are formed on the upper ends 47 and 48 respectively and the end 48 is provided with the usual lower edge flap 54. A small projection or tab 45 55 is also formed on the inner side 44 for a purpose to be described.

The display card and the provision for supporting the same is somewhat different in this form of our invention. An extension 50 from the upper edge of the upper inner end 47 is separated by a substantially U-shaped slit 56 to form a display card 57 and a card brace 58 having an end flap 59.

The easel in this form of our invention 55 is formed of a separate piece of material secured to the outer bottom 40 and comprising an easel or support 60, an easel brace 61 and a securing device comprising a center strip 62 and side strips 63, the center 60 strip having a V-shaped slit therein forming a tongue 64 adapted to extend through a slit 65 in the outer bottom 40.

The procedure of folding this second form 65 of box is substantially the same as in the first form, the tab 55 serving to prevent in-

ward displacement of the side 44. The display brace 58 is bent downward as indicated in Fig. 10 and its flap 57 is inserted above the outer bottom 40, thus holding the display card in its desired position. The 70 easel is folded as indicated in Fig. 10 and the tongue 64 is inserted through the slit 65 to hold the easel in position.

Having thus described two forms of our invention, it will be evident that the boxes 75 herein shown are of simple construction, and, when folded, provide receptacles which are attractive in appearance and which are particularly well adapted for the display of articles of sale, such as fruit or confectionery, and particularly in retail stores.

Having thus described our invention, it will be evident that changes and modifications can be made therein within the spirit 80 and scope of our invention as set forth in the claims, and we do not wish to be otherwise limited to the details herein disclosed, but what we claim is:—

1. A folding box formed from a blank cut and scored to form an outer bottom, extensions at the side thereof forming outer and inner sides for the box and locking side flaps therefor, an extension from the end of one inner side forming an inner upper end, an extension from the end of the opposite outer side forming an outer upper end and having an end locking flap thereon, and an extension from the lower end of the outer bottom forming outer and inner lower end portions. 90

2. A folding box formed from a blank cut and scored to form an outer bottom, extensions at the side thereof forming outer and inner sides for the box and locking side flaps therefor, an extension from the end of one inner side forming an inner upper end, a display card projecting from the upper edge of said end, an extension from the end of the opposite outer side forming an outer upper end, and an extension from the lower end of said outer bottom forming outer and inner lower end portions and an inner bottom portion. 105

3. A folding box formed from a blank cut and scored to form an outer bottom, extensions at the side thereof forming outer and inner sides for the box and locking side flaps therefor, an extension from the end of one inner side forming an inner upper end, a display card projecting from the upper edge of said end, an extension from the end of the opposite outer side forming an outer upper end, a brace for said display card, and an extension from the lower end of said outer bottom forming outer and inner lower end portions and an inner bottom portion. 115

4. A folding box formed from a blank cut and scored to form an outer bottom, extensions at the side thereof forming outer and inner sides for the box and locking side 120

flaps therefor, an extension from the end of one inner side forming an inner upper end, a portion projecting from the upper edge thereof and forming a display card and a brace therefor, said brace having a locking end flap, an extension from the end of the opposite outer side forming an outer upper end and having an end locking flap therefor, and an extension from the lower end 10 of said outer bottom forming outer and inner lower end portions and an inner bottom portion.

5. A folding box formed from a blank cut and scored to form an outer bottom, 15 extensions at the side thereof forming outer and inner sides for the box and locking side flaps therefor, an extension from the end of one inner side forming an inner upper end, a projection from the upper edge thereof 20 forming a display card, a portion of said projection being formed by a U-shaped slit as a brace for said card, and having a locking end flap, an extension from the end of the opposite outer side forming an outer 25 upper end, and an extension from the lower end of said outer bottom forming a double lower end and an inner bottom portion.

6. A folding box formed from a blank cut and scored to form an outer bottom, 30 extensions at the side thereof forming outer and inner sides for the box and locking side flaps therefor, an extension from the end of one inner side forming an inner upper end, an extension from the end of the opposite 35 outer side forming an outer upper end and having an end locking flap thereon, an extension from the lower end of the outer bottom forming outer and inner lower end portions and an inner bottom portion, and an 40 easel projecting from the upper end of said

outer portion and having a brace cooperating with said bottom portion to hold said easel and box in position.

7. A folding box formed from a blank cut and scored to form an outer bottom, 45 extensions at the side thereof forming outer and inner sides for the box and locking side flaps therefor, an extension from the end of one inner side forming an inner upper end, an extension from the end of the opposite 50 outer side forming an outer upper end and having an end locking flap thereon, an extension from the lower end of the outer bottom forming outer and inner lower end portions and an inner bottom portion, and an 55 easel projecting from the upper end of said outer bottom and having a brace and means to lock said brace to said outer bottom.

8. A folding box formed from a blank cut and scored to form an outer bottom, 60 extensions at the side thereof forming outer and inner sides for the box and locking side flaps therefor, an extension from the end of one inner side forming an inner upper end, an extension from the end of the opposite 65 outer side forming an outer upper end and having an end locking flap thereon, and an extension from the lower end of the outer bottom forming outer and inner lower end portions and an inner bottom portion, one 70 of said inner box sides having a projecting tab confined between the inner and outer bottom portions of the box when the latter is folded and preventing displacement of said inner side. 75

In testimony whereof we have hereunto affixed our signatures.

HENRY C. DURICK.

JOHN T. BIRD.
